US00D556002S

(12) **United States Design Patent** (10) **Patent No.:** **US D556,002 S**
Ino (45) **Date of Patent:** **** Nov. 27, 2007**

(54) **ELECTRIC IMPACT DRIVER BODY**

(75) Inventor: **Tomoaki Ino**, Hikone (JP)

(73) Assignee: **Matsushita Electric Works, Ltd.**,
Osaka (JP)

(**) Term: **14 Years**

(21) Appl. No.: **29/285,396**

(22) Filed: **Mar. 28, 2007**

(30) **Foreign Application Priority Data**

Oct. 24, 2006 (JP) 2006-029037

(51) **LOC (8) Cl.** **08-05**

(52) **U.S. Cl.** **D8/68**

(58) **Field of Classification Search** D8/14.1,
D8/61-70; 81/57.11, 429, 454-456, 469,
81/489; 173/13, 104, 114, 168-171, 178,

(57) **CLAIM**

The ornamental design for an electric impact driver body, as shown and described.

DESCRIPTION

FIG. 1 is a front perspective view of the design according to the invention.

FIG. 2 is a back perspective view of the design according to the invention.

FIG. 3 is a front view of the design according to the invention.

FIG. 4 is a rear view of the design according to the invention.

FIG. 5 is a left view of the design according to the invention.

FIG. 6 is a right view of the design according to the invention.

FIG. 7 is a top view of the design according to the invention.

FIG. 8 is a bottom view of the design according to the invention; and,

FIG. 9 is a front perspective view of the design showing an attached battery pack in broken lines according to the invention.

The elements shown in broken lines are for illustrative purposes only and form no part of the claimed design.
